(57) **CLAIM**

The ornamental design for a stretchable sleeve, as shown and described herein.

DESCRIPTION

FIG. 1 is a perspective view of a stretchable sleeve showing our new design when the sleeve is collapsed onto itself;

FIG. 2 through FIG. 7 illustrate various views of a stretchable sleeve as it would be present over a cylindrical body such as an arm or leg.

FIG. 2 is a top view thereof;

FIG. 3 is a front view thereof;

FIG. 4 is a bottom view thereof, which is a view when the sleeve shown in FIG. 2 is rotated around on its horizontal axis (i.e., along the length of the sleeve) by 180°;

FIG. 5 is a rear view thereof, which is a view when the sleeve shown in FIG. 3 is rotated around on its horizontal axis (i.e., along the length of the sleeve) by 180°; and

FIG. 6 is a left end side view; and,

FIG. 7 is a right end side view.
